UNITED STATES PATENT OFFICE.

ROBERT F. CARPENTER, OF CLEVELAND HEIGHTS, OHIO, ASSIGNOR TO THE SANY-METAL PRODUCTS COMPANY, OF CLEVELAND, OHIO, A CORPORATION OF OHIO.

METHOD OF FORMING PRESSED-METAL HINGES.

Application filed June 9, 1921 Serial No. 476,211.

This invention relates to improvements in pressed metal hinge members and the method of forming the same.

The objects of this invention are to provide 5 a hinge construction of pressed metal and to devise an improved method of forming the same.

Other objects of this invention will appear 10 from the following description and claims when considered together with the accompanying drawing.

Fig. 1 shows the form of blank metal from 15 which the hinge members are pressed up; Fig. 2 is an inverted plan view of the same metal blank after being pressed; Fig. 3 shows the same pressed metal blank in elevation; Fig. 4 is a perspective view of the lower hinge member formed from the blank; and Fig. 5 is a perspective view of the upper hinge mem- 20 ber formed from a similar blank.

The metal blank shown in Fig. 1 comprises 25 the end portions 1 and 2, the knuckle portion 3 which has the extension 4, and the intermediate portions 5 and 6 joining the end and 30 knuckle portions. The extension 4 is spaced from the end portions as indicated at 7 and the intermediate portions are curved as indicated at 8. The edges of the intermediate portions on the other side of the blank are 35 also curved as indicated at 9 and join the knuckle portion in the curved edge 10. The screw holes 11 are provided in the end por- 40 tions.

Starting with this flat metal blank, the end 45 portions are pressed up into the flanges 12 and 13 to form brackets for engaging the door post. The edges of the intermediate or neck portions 5 and 6 are also pressed into flanges 14 and 15. The shoulder 16 is pressed 50 into the blank to form the extension 4 of reduced diameter, and the knuckle portion of the blank is also pressed so as to lie in a plane between that of the flanges 12 and the neck portions, the knuckle and intermediate neck 55 portions joining each other in the curved portion 17.

The next step consists in closing the two halves of the blank upon each other so as to 55 form the complete hinge member indicated in Fig. 4. The flanges 13 are thus brought into alignment with each other while the curved portions 14 and 15 abut each other, thereby forming a hollow neck portion. The hinge member is then ready to be applied to 60 the door post by means of screws through the

holes 11, this form of hinge member being adapted for use at the lower portion of the door as part of a gravity roller hinge.

Then in order to form the hinge member illustrated in Fig. 5, the same blank as shown in Fig. 1 can be used by cutting off or omitting the extension 4 and forming the edge along this side of the blank like that on the other side of the blank, that is, with the curved edges 9 and 10. In other words, the blank used to form this particular hinge member is symmetrical not only with respect to the transverse axis but also with respect to the longitudinal axis therethrough. This blank is then pressed up so as to form the 70 flanges as already described in connection with the first form except as to the reduced portion 4. The hinge member is then completed by closing the two halves of the blank upon each other, thereby abutting the flanges 75 14 and 15 against each other at the two ends of the neck portion. This hinge member is then ready to be applied to the upper portion of the door post.

From the above it will be seen that I have 80 not only provided hinge members pressed up from blank metal, which means a decrease in the cost of manufacture, but have also devised a method of pressing up such hinge members from metal blanks which lends to 85 the facility with which such hinge members can be manufactured. A further advantage resides in the fact that the blanks after they have been pressed into the form illustrated in Figs. 2 and 3, can be shipped and then completed by closing the two halves of the blanks upon themselves. This means a decided saving in the space required for shipping of 90 such hinge members.

Other advantages resulting from this in- 95 vention will suggest themselves to those who are familiar with the art to which it relates.

What I claim is:

1. A blank for a hinge member, comprising a knuckle portion, each end portion of said knuckle portion being curved and continuing into a neck portion, said neck portions extending substantially parallel to said knuckle portion and each of said neck portions continuing into an arm of an angular bracket portion, each bracket portion comprising two arms, the second arm thereof constituting the end portion of the blank and the two halves of the blank being substantially symmetrical.

2. A blank for a hinge member, comprising a knuckle portion, each end portion of said knuckle portion being curved and continuing into a neck portion, said neck portions 5 extending substantially parallel to said knuckle portion and each of said neck portions continuing into an arm of an angular bracket portion, the edges of said neck portions being flanged and each merging into the 10 adjacent arm of said bracket portion, bracket portion comprising two arms, the second arm thereof constituting the end portion of the blank, and the two halves of the blank being substantially symmetrical with respect to the 15 transverse axis thereof.

3. The method of forming a hinge member from a sheet metal blank having a knuckle portion, end angular bracket portions and intermediate neck portions, consisting in 20 pressing said blank to completely form the angular brackets and partially form the knuckle, and then completing the hinge member by pressing the knuckle to substantially cylindrical shape and thereby bringing the 25 neck portions into substantially parallel relation.

4. The method of forming a hinge member from a sheet metal blank having a knuckle portion, end angular bracket portions and intermediate neck portions, consisting in pressing 30 said blank to completely form the angular brackets and simultaneously partially form the knuckle, and then completing the hinge member by pressing the knuckle to substantially cylindrical shape and thereby bringing the neck portions into substantially parallel relation.

5. The method of forming a hinge member from a sheet metal blank having a knuckle portion, end bracket portions and intermediate neck portions, consisting in pressing 40 said blank to completely form brackets, to provide the neck portions with inwardly extending strengthening flanges, and to partially form the knuckle, and then completing the hinge member by pressing the knuckle into substantially cylindrical shape and thereby bring the neck portions into substantially parallel relation.

In testimony whereof I hereby affix my 45 signature.

ROBERT F. CARPENTER.

CERTIFICATE OF CORRECTION.

Patent No. 1,691,109.

Granted November 13, 1928, to

ROBERT F. CARPENTER.

It is hereby certified that error appears in the printed specification of the above numbered patent requiring correction as follows: Page 2, line 10, claim 2, for the word "said" read "a" and after the word "portion" insert the word "each"; and that the said Letters Patent should be read with these corrections therein that the same may conform to the record of the case in the Patent Office.

Signed and sealed this 8th day of January, A. D. 1929.

(Seal)

**M. J. Moore,
Acting Commissioner of Patents.**
